UNITED STATES PATENT OFFICE.

LAWRENCE J. DESENBERG, OF LOS ANGELES, CALIFORNIA.

CHANGE-MAKING MACHINE.

1,135,165.

Specification of Letters Patent.

Patented Apr. 13, 1915.

Application filed March 23, 1914. Serial No. 826,589.

To all whom it may concern:

Be it known that I, LAWRENCE J. DESENBERG, a citizen of the United States, residing at Los Angeles, in the county of Los Angeles and State of California, have invented a new and useful Change-Making Machine, of which the following is a specification.

This invention relates to a machine which is designed to automatically deliver the amount of change.

Referring to the drawing: Figure 1 is a front elevation of the upper portion of the machine. Fig. 2 is a horizontal section on line x^2-x^2 , Fig. 3. Fig. 3 is a vertical section on line x^3-x^3 , Fig. 4. Fig. 4 is a vertical section on line x^4-x^4 , Fig. 3. Fig. 5 is a vertical section on line x^5-x^5 , Fig. 3, showing one side portion only. Fig. 6 is a perspective of a portion of a coin ejector and slotted arm. Fig. 7 is a perspective of the device as combined with a cash register. Fig. 8 is a section on line x^8-x^8 , Fig. 2. Fig. 9 is a side elevation in detail of the movable pinion, its adjusting means, and adjacent portion of its associated gear, showing the pinion out of mesh with the gear. Fig. 10 is a view similar to Fig. 9 showing the position of the parts when the pinion is engaged with the gear.

The machine comprises a case 1, the front end of which is provided with a series of coin tubes a, b, c, d, e, f , for respectively holding coins of the denomination of dollars, fifty cent pieces, twenty-five cent pieces, ten cent pieces, five cent pieces and pennies. The coin tubes are all carried by a bottom plate A and a back plate B which slides in ways C so that the coin tubes with their contents may be lifted out bodily and stored in a safe when desired. At the upper end of each coin tube is a slot 2 to enable the tube to be filled with coins corresponding with that denomination, and at its lower end each coin tube has a discharge slot 3 through which the coin which is to form the change is to be ejected. A series of slots 4 are arranged in the front of the case and guided in the slots 4 are operating levers 5 which are pivoted at 6 inside the case at the rear thereof, and the front end of each lever carries a button 7 on which is printed the denomination of the coin which is controlled by that lever.

Below the coin tubes is a shelf 8 which supports the lowermost coins and also serves as a guide for a series of coin ejectors 9

which are arranged to slide under the respective coin tubes to eject the lowermost coins from the tubes. The rear end of each ejector rod 9 is connected by a connecting rod 12 with a pinion 13, whereby rotation of the pinion 13 will reciprocate the ejector 9 and cause the ejector to push out a coin from the coin tube at each forward movement of the ejector. Each pinion 13 is suspended by a bell crank lever 14 pivoted at 15 to a stationary bracket 16, and the other arm of the bell crank lever 14 is arranged underneath an arm 17' which projects down rigidly from the operating lever 5. Arranged at the rear of the respective pinions 13 are gears 18 all of which are rigidly mounted on a shaft 19 which is provided with a crank 20. A roller ratchet 20^a having its drum 20^b secured to the casing 1 prevents rearward rotation of the shaft. Whenever one of the operating levers 5 is depressed, its arm 17' acts against the bell crank lever 14 to swing the associated pinion 13 into mesh with the corresponding gear 18 and then by rotating the crank 20, the gear will revolve the pinion 13 a corresponding number of times which will give a corresponding number of outward sliding movements of the ejector 9 and will eject one coin at each outward stroke.

The escapement bars 17 are rigidly secured to the operating levers 5 and project downwardly therefrom, and each consists of a slotted bar as shown. Pivoted to each ejector bar 9 is a pawl 23 having a roller 23^a which engages in the concave notches 23^b on the escapement bar, and is held yieldingly in engagement therewith by a coil spring 23^c and which acts to lift the escapement bar a distance of one notch during each forward stroke of the ejector bar 9. The escapement bar has a series of notches 23^d on its opposite face which are engaged by the retaining pawl 23^e to yieldingly hold the escapement bar and its operating lever 5 in the position set.

When it is desired to make change, the operator will push down one or more of the operating levers 5 according to the denomination of coin desired, moving down the lever or levers a distance in the slots 4 to correspond with the number of coins to be ejected. For this purpose each slot 4 is provided with a series of graduations with indicating numerals, as clearly shown in Fig. 1. Thus, assuming that the customer has made

a purchase amounting to one cent, and has given in payment a five cent piece, and four cents is to be returned as change to the customer, the operator presses down the operating lever 5 to the indicating numeral 4 at the coin tube *f*, and in thus depressing the operating lever 5, it moves down the escapement bar 17 sliding over the ejector bar 9. As the operating pawl 23 and retaining pawl 23^a are both yieldingly held against the escapement bar, they do not prevent its downward movement during the setting operation, as the rounded notches are sufficiently shallow. During this downward movement of the operating lever 5, the arm 17' has tilted the bell crank lever 14 and moved the associated pinion 13 into mesh with the corresponding gear 13, and when the bell crank lever 14 has been tilted downward by the arm 17' sufficient to place the pinion 13 into mesh with its corresponding gear, the angular position of the bell crank lever is such that its upper end permits the arm 17' to continue its downward movement and hold the bell crank lever and associated pinion in this position during such further downward movement of the arm 17', and the bell crank lever and pinion remain in this position until the arm 17' has again raised sufficiently to permit the bell crank lever to swing back. Figures 9 and 10 show this action in detail. The operator then turns the crank 20, which rotates the pinion 13, and as the pinion 13 rotates, it reciprocates the ejector 9 and at each outward stroke of the ejector a penny is ejected from the coin tube *f*. During each outward movement of the ejector bar 10, the pawl 23 pushes up the escapement bar 17 a distance of one notch, and as the operating lever had been moved down four points to eject four pennies, it will be moved completely back by four strokes of the ejector bar, and after having been thus moved back to normal position, the arm 17' will release the bell crank lever 14 and permit the pinion 13 to be moved out of mesh with gear 18 by means of spring *x* so that even though gear may be revolved more than sufficient to eject the four coins, that there will be only four coins ejected, as the revolutions of gear 18 do not actuate the ejecting mechanism after the operating lever 5 has thus been automatically returned to its normal position at the top of its slot 4.

55 The operation for making change with coins of any other denomination will readily be understood from the foregoing. It is apparent that the change need not be made entirely in coins of one denomination. Thus 60 if the customer pays a twenty-five cent coin for a ten cent purchase and fifteen cents in change is to be given him, the operator will press down the two levers 5 corresponding with coin tubes *d* and *e*, depressing each lever one point, and upon rotating the crank,

the ejectors for the coin tubes *d* and *e* will be moved out to eject one coin each, a ten cent piece and a five cent piece, and this one stroke will act upon the escapements 17 to restore the operating levers 5 to normal position, so that no more coins will be ejected, and thus fifteen cents in change is provided. 70

Referring to the last transaction, if it should so happen that the machine should have no five cent coins in tube *e*, the operator would have depressed the lever of coin tube *d* one point for the ten cent piece, and would depress the lever of coin tube *f* five points to give five pennies, and then upon turning the crank, the ejector of the tube *d* would be actuated once, whereupon its operating lever would be restored to normal position, while the ejector of the tube *f* would be operated five times before its operating lever would be returned to normal position, 80 thereby giving change of one ten cent piece and five pennies. A bell 24 is arranged inside the case and is adapted to be struck by an arm 25 which is carried on the gear shaft, the arm being so arranged that it will strike 85 the bell during the initial movement of the shaft. 90

What I claim is:

1. In a change making machine, a plurality of coin holders, ejectors for the respective coin holders, means for operating said ejectors comprising a gear, a pinion for each ejector, a connecting rod between each pinion and its associated ejector, selecting means for moving the pinion into mesh with the gear, and means operating automatically to disconnect the pinion from the gear after the desired number of ejections have been performed. 95

2. In a change making machine, a plurality of coin holders, ejectors comprising slides in the lower ends of the holders, a bodily movable pinion for each slide connected to reciprocate the slide when the pinion is rotated, a pivoted arm carrying each pinion, an operating gear with which the pinion is adapted to mesh, a plurality of selecting levers, means operated by the respective selecting levers for moving the respective arms and the pinions carried thereby into mesh with the respective gears. 105 110 115

3. In a change making machine, a plurality of coin holders, ejectors comprising slides in the lower ends of the holders, a bodily movable pinion for each slide connected to reciprocate the slide when the pinion is rotated, a pivoted arm carrying each pinion, an operating gear with which the pinion is adapted to mesh, a plurality of selecting levers, means operated by the respective selecting levers for moving the respective arms and the pinions carried thereby into mesh with the respective gears upon a downward movement of the selecting levers, and means operating to automatically 120 125 130 135

restore a selecting lever and disengage its associated pinion after its desired number of ejections have been performed.

4. In a change making machine, a plurality of coin holders, ejectors comprising slides in the lower ends of the holders, a bodily movable pinion for each slide connected to reciprocate the slide when the pinion is rotated, a pivoted arm carrying each pinion, an operating gear with which the pinion is adapted to mesh, a plurality of selecting levers, means operated by the respective selecting levers for moving the respective arms and the pinions carried thereby into mesh with the respective gears, and audible signal means operated by the movement of a gear.

5. In a change making machine, a series of coin holders, each having a slot at the top thereof for the insertion of coins, a slot at the bottom for the ejection of coins, an ejector slide in the bottom of each holder, a

plurality of pinions, a connection for each pinion to a slide, a pivoted arm supporting each pinion, a shaft, a crank for operating the shaft, a plurality of gears rigidly secured to the shaft and adapted to drive the respective pinions when the latter are in mesh with any of the gears, a plurality of selecting levers extending between the coin holders, means operated by the selecting levers for moving the associated pinions into mesh with the corresponding gears, and means for automatically restoring a selecting lever and disengaging its associated pinion from its gear when the desired number of ejections has been made.

In testimony whereof, I have hereunto set my hand at Los Angeles, California this 17th day of March, 1914.

LAWRENCE J. DESENBERG.
